UNITED STATES PATENT OFFICE

AUGUST H. KATTERJOHN, OF DENVER, COLORADO, ASSIGNOR TO THE DENVER ROCK DRILL MANUFACTURING COMPANY, OF DENVER, COLORADO, A CORPORATION OF DELAWARE

SPRING HANDLE FOR DRIFTING DRILLS

Application filed September 30, 1926. Serial No. 138,778.

As is well known it is the custom to mount a drifting drill on a shell and to feed it to its work by means of a screw. For these purposes the barrel of the tool is usually provided with oppositely outstanding guide flanges that are slidably engaged in guideways of the shell. Between these flanges is formed a boss or sleeve in which is secured the nut that is engaged by the feed screw.

10 The object of the present invention is to provide a handle structure that may be mounted on a tool of this character when the latter is removed from the shell, thus making the drill adaptable for more general use. A further object is to provide a yielding mounting for such handle.

15 In the accompanying drawings Figure 1 is a side elevation of a well known type of drifting drill showing the handle attachment in place thereon.

Figure 2 is a longitudinal sectional view of the same.

20 Figure 3 is a horizontal sectional view taken substantially on the line 3—3 of Figure 2.

Figure 4 is an end elevation of the handle attachment viewed in the direction of the arrow 4 of Figure 3.

25 Figure 5 is a cross sectional view through the barrel with the barrel and handle and is taken on the line 5—5 of Figure 2.

In the embodiment disclosed the barrel of the drifting drill is shown at 6 and may be of any well known construction. It is provided on its lower side with an enlargement having oppositely outstanding longitudinally disposed guide flanges 7. These flanges as is well known are adapted to slidably engage in guideways of a shell. The enlargement is further provided with a central boss or sleeve 8 disposed longitudinally of the barrel 6 between the flanges 7. This boss or sleeve receives and holds the nut that is engaged by the usual feed screw of the drifter. It is believed unnecessary to further describe or illustrate the tool and the above instrumentalities have been set forth in order to make clear the means by which the hereinafter described handle is mounted on the tool when

the latter has been disassociated from its shell and feeding means.

A handle frame or cradle is provided consisting of spaced side arms 9, across the rear ends of which extends a bolt 10 carrying a plurality of handle grips 11, one of these grips being preferably located between the arms, the other two extending transversely beyond the outer sides of said arms. The front end portions of the arms are provided in their inner sides with longitudinal grooves 12, constituting guideways that receive the guide flanges 7 of the tool 6 so that the handle frame and handle will slide upon the tool.

The front ends of the side arms 9 are connected by a downwardly curved cross bow 13. Extending forwardly from the central portion of this cross bow is a longitudinally disposed arm 14 terminating in an upstanding ear 15. The front end of a plunger rod 16 is fixed in this ear by means of a screw thread and held securely with a spring lock washer and nut, said plunger rod extending centrally between the handle arms 9 in a lower plane than the guideways 12. Surrounding the plunger rod is a sleeve 17 in which said plunger rod is slidably mounted. A plunger head 18 is fixed to the rear end of the plunger rod 16 and is slidably mounted in the rear end of the sleeve 17. Surrounding the rod 16 between the plunger head 18 and an abutment shoulder 19 formed in the front end of the sleeve 17, is a coiled spring 20, which obviously resists the forward movement of the plunger head and consequently of the plunger rod with respect to the sleeve 17.

20 The rear end of the sleeve 17 is of a size to fit snugly in the boss or sleeve 8 of the tool barrel 6 and said sleeve 17 is provided with an abutment enlargement 21 that is adapted to bear against the front end of the sleeve or boss 8. This abutment enlargement is preferably angular to receive a wrench. The rear end of the sleeve 17 is externally threaded to receive a holding nut 22 with which may be associated a lock washer 23. These two serve with the enlargement 21 to rigidly secure the sleeve 17 in the sleeve or boss 8.

25 With this construction it will be evident

that a drifting drill may be removed from its shell, the feed nut disengaged and the present handle structure applied, thus making the tool available for other purposes. 5 Moreover, when the sleeve 17 is in place on the tool and the handle bars are slidably engaged with the guide flanges a yielding handle is provided, for when forward pressure is exerted against the handle grips the handle frame can move forwardly but this 10 movement is resisted by the spring 20, inasmuch as the plunger head 18 will move forwardly with the handle and thus compress the spring 20 in the sleeve 17.

15 From the foregoing, it is thought that the construction, operation and many advantages of the herein described invention will be apparent to those skilled in the art, without further description and it will be understood that various changes in the size, shape, 20 proportion and minor details of construction may be resorted to without departing from the spirit or sacrificing any of the advantages of the invention.

25 What I claim is:—

1. The combination with a fluid operated tool having opposite guides and a longitudinally disposed sleeve between the guides, of a handle the tool and a frame carrying the 30 handle and having portions slidably mounted on the guides and in the sleeve.

2. The combination with a fluid operated tool having opposite guides and a longitudinally disposed sleeve between the guides, of a handle the tool and a frame carrying the handle and having portions slidably mounted on the guides and in the sleeve, and a spring engaged with one of the portions for resisting the sliding movement in one direction. 40

3. The combination with a fluid operated tool having a barrel, said barrel being provided with guides, and a longitudinal sleeve between the guides, of a handle having a frame provided with slides engaged with the guides, a plunger slidably mounted in the sleeve, and a spring in the sleeve that resists the movement of the plunger. 45

4. The combination with a tool barrel having opposite guide flanges and a longitudinally disposed sleeve between the flanges, of a second sleeve fixed in the first sleeve, a handle in the rear of the barrel having forwardly extending side arms provided with grooves that slidably receive the guides, a plunger rod carried by the front ends of the side arms and slidably engaged in the second sleeve, a plunger head on the rod, and a spring in the second sleeve borne against by the plunger head. 50

5. A handle attachment for drifting drills, comprising a handle grip, a frame carrying said grip and having guideways for receiving the guide flanges of a drifting drill, a spring mounting for resisting the move- 55

ment of the handle, carried by said frame, and means for securing said mounting in the feed nut sleeve of the drifting drill.

6. A handle attachment for drifting drills, comprising a handle grip, a frame carrying said grip and having forwardly extending arms provided with guideways for receiving the guide flanges of a drifting drill, a plunger rod connected to the front end of the arms and extending rearwardly between the same, a sleeve surrounding the rod and in which it is slidably engaged, a spring in the sleeve that resists the relative movement of the rod and sleeve, and means for fixing the sleeve in the feed nut sleeve of the drifting drill. 70 75

7. A spring handle for a rock drill, comprising a cradle having guideways to receive the shell guides of a rock drill whereon said cradle is adapted to slide, means for connecting the cradle to the drill, a spring acting against the cradle and the drill to cushion the cradle, and grip members on the cradle for manipulating the rock drill. 80 85

8. A spring handle adapted to be substituted for the shell of a rock drill, comprising a cradle having internal guideways to cooperate slidably with the shell guides of the rock drill, a bolt for holding the cradle on the shell guides, a spring acting against the cradle and a rock drill for holding the cradle in retracted position, and grip members on the cradle for manipulating the rock drill. 90 95

9. In a percussive tool, a cylinder having guides thereon, a hollow sleeve member carried by said cylinder, a bolt extending through said sleeve, a handle supporting member cooperating with said bolt and slidably mounted on said guides, and a compression spring encircling said bolt and engaging said sleeve and resisting the movement of the handle supporting member. 100 105

10. In a percussive tool, a cylinder having outstanding guide flanges and a hollow sleeve member, a handle having a frame slidably mounted on the guide flanges, and means engaged in the sleeve for anchoring the handle frame to the cylinder and permitting its slid- 110 able movement on the guide flanges. 115

11. In a percussive tool, a cylinder having outstanding guide flanges and a hollow sleeve member, a handle having a frame slidably mounted on the guide flanges, means engaged in the sleeve for anchoring the handle frame to the cylinder and permitting its slid- 120 able movement on the guide flanges, and a spring engaged with the anchoring means for yield- 125 ingly resisting the sliding movement of the handle frame.

12. In a percussive tool, a cylinder having outstanding guide flanges and a hollow sleeve member, a handle having a frame slidably mounted on the guide flanges, means engaged in the sleeve for anchoring the handle 130

frame to the cylinder and permitting its slide-
able movement on the guide flanges, said
means including a bolt that passes through
the sleeve, and a spring on the bolt for yield-
ingly resisting the sliding movement of the
handle frame.

13. In a percussive tool having outstanding
guide flanges and a hollow boss, a handled
frame having guideways that are slideable
upon the flanges, a sleeve fixedly mounted in
the boss, a bolt engaged with the handled
frame and passing through the sleeve, and a
spring on the bolt bearing against the sleeve
and resisting the sliding movement of the
handled frame.

14. A handle attachment for drifting drills
comprising a frame shell having internal
guideways to receive the guide flanges of a
drill, a handle carried by the frame, a sleeve
for engagement in the boss of the drill, a bolt
that passes through the sleeve and is engaged
with the frame shell, and a spring on the bolt
that bears against the sleeve.

15. A handle attachment for drifting drills
comprising a frame shell having internal
guideways to receive the guide flanges of a
drill, a handle carried by the frame, a sleeve
for engagement in the boss of the drill, said
sleeve having an abutment shoulder for en-
gagement with one end of the boss and a
holding nut threaded on the other end of the
sleeve for holding the sleeve in the boss, a
bolt that passes through the sleeve and is en-
gaged with the frame shell, and a spring on
the bolt that bears against the sleeve.

In testimony whereof, I affix my signature.
AUGUST H. KATTERJOHN.
